ATTORNEY

UNITED STATES PATENT OFFICE.

JOTHAM P. CARPENTER, OF ATTLEBOROUGH, MASSACHUSETTS.

SEPARABLE BUTTON.

SPECIFICATION forming part of Letters Patent No. 224,143, dated February 3, 1880.

Application filed December 11, 1879.

To all whom it may concern:

Be it known that I, JOTHAM P. CARPENTER, of Attleborough, county of Bristol, and State of Massachusetts, have invented certain new and useful Improvements in Buttons, of which the following is a full, clear, and exact description, reference being had to the accompanying drawings.

This invention has reference to an improvement in separable buttons; and it consists in the peculiar arrangement of a fixed central pin secured to a disk and surrounded by an annular slotted rim, in which a fork is made to slide, operated by a push-pin and held by a spring, so that the shoe provided with a tubular shank may be firmly held, as will be more fully set forth hereinafter.

Referring to the drawings, Figure 1 is a perspective view of the improved button, a part of the shoe being shown as cut away, so as to show the device more clearly. Fig. 2 represents the various parts as detached in perspective view. Fig. 3 is a view of the button, showing the device when the two parts are secured together. Fig. 4 is a view of the button, showing the device when the shoe is released.

In the drawings, A represents the disk of the button, and B the shoe. a is the disk to which the post b and the slotted annular rim c are secured, and which is secured to the button A by solder. d are the slots in which the slide e moves and by which it is held.

The slide e is stamped out of sheet metal, and has a central enlargement, f, into which the tubular post l, provided with the shoulder m, can freely enter, guided by the post b. g is a contracted portion of the slide e, which, when slid over the shoulder m, firmly secures

the tubular post and the shoe to the button. h and i are stops, by which the movement of the slide e is controlled by the stop coming in contact with the annular rim e.

The slide e is provided with a pusher, K, which extends through the rim of the button. The tubular post l is secured to the shoe B; and n is a spring, made of wire bent into a loop, as shown. The ends of the wire are bent at a right angle and enter the recess o in the slide e.

As the slide is firmly held in the slot d the shoe will be firmly secured when the contracted portion g is over the shoulder m on the tubular post l, and as this post is guided by the post b the button can be easily secured, and when secured is more rigid than are buttons as heretofore made.

This improved device is simple and durable, and the stops on the slide limit the motion, so that the device cannot be strained or injured in use.

Having fully described my invention, what I claim as new, and desire to secure by Letters Patent, is—

In a separable button, the button A, provided with a disk, a, supporting a post, b, and a slotted rim, c, in combination with the shoe B, provided with the shoulder m, the slide e, having stops h and i, the pusher K, and looped spring n, all constructed and arranged to operate substantially as shown and described.

In witness whereof I have hereunto affixed my name.

JOTHAM P. CARPENTER.
